3 Claims 10

ABSTRACT OF THE DISCLOSURE

Pharmaceutical compositions comprising essentially compounds of the Formulae I and II

in which each of Ph_1 and Ph_2 stands for a 1,2-phenylene radical, R_1 for hydrogen or an aromatic radical and R_2 for an aliphatic, araliphatic or aromatic radical, their N-oxides and quaternaries and the salts of these compounds. The compositions of the invention are useful, inter alia, as analgesic agents.

The present invention concerns and has for its object the provision of pharmaceutical compositions comprising essentially a 4-aminoalkylamino-quinazoline and a 1-aminoalkoxy-benzimidazole.

More particularly the compositions of the invention contain as the active main ingredients compounds of the Formulae I and II

in which each of Ph_1 and Ph_2 stands for a 1,2-phenylene radical, R_1 for hydrogen or an aromatic radical and R_2 for an aliphatic, araliphatic or aromatic radical, their N-oxides and quaternaries and the salts of these compounds.

The 1,2-phenylene radicals Ph_1 and Ph_2 may be unsubstituted or substituted by one or more than one of the same or of different substituents attached to any of the four positions available for substitution. Such substituents are primarily the following: lower alkyl, e.g. methyl, ethyl, n- or i-propyl or -butyl, etherified hydroxyl, especially lower alkoxy, e.g. methoxy, ethoxy, n- or i-propoxy, n- or tert. -butoxy, lower alkenyloxy, e.g. allyloxy, lower alkylenedioxy, e.g. methylenedioxy, esterified hydroxyl, particularly halogeno, e.g. fluoro, chloro or bromo, trifluoromethyl, nitro, unsubstituted or substituted amino, such as di-lower alkylamino, e.g. dimethylamino or diethylamino, acyl, such as lower alkanoyl, e.g. acetyl, propionyl or pivalyl, benzoyl or pyridoyl, e.g. p-toluoxy or nicotinoyl, or sulfamyl.

Above all the 1,2-phenylene radicals Ph_1 and Ph_2 stand for 1,2-phenylene, (lower alkyl)-1,2-phenylene, (lower alkoxy)-1,2-phenylene, (halogeno)-1,2-phenylene, (trifluoromethyl) - 1,2 - phenylene, (nitro)-1,2-phenylene,

2

(amino)-1,2-phenylene, (di-lower alkylamino)-1,2-phenylene, (lower alkanoyl)-1,2-phenylene or (sulfamyl)-1,2-phenylene.

An aliphatic or araliphatic radical representing R_2 is, for example, lower alkyl, e.g. methyl, ethyl, n- or i-propyl, straight or branched chain butyl, pentyl, hexyl or heptyl bound in any position, lower alkenyl, e.g. allyl or methallyl, cycloalkyl or cycloalkyl-lower alkyl having from three to eight, preferably from five to six, ring carbon atoms, e.g. cyclopropyl, cyclopentyl, cyclohexyl or cycloheptyl; cyclopropyl-methyl, cyclopentyl-methyl, 3-cyclopentyl-propyl, cyclohexyl-methyl, 2-cyclohexyl-ethyl or cycloheptyl-methyl, cycloalkenyl or cycloalkenyl-lower alkyl having from five to eight, preferably from five to six, ring carbon atoms, e.g. 1-cyclopentenyl, 1-cyclohexenyl, 3-cyclohexenyl, 1-cycloheptenyl, 3-cycloheptenyl or 1-cyclooctenyl; 1-cyclopentenyl-methyl, 1-cyclohexenyl-methyl or 2-(3-cyclohexenyl)-ethyl, or monocyclic carbocyclic aryl-lower alkyl, e.g. benzyl, 1- or 2-phenyl-ethyl. Said aralkyl radicals may be unsubstituted or substituted in the aromatic moiety by one or more than one of the same or of different substituents attached to any of the positions available for substitution. Such substituents are exemplified by those listed for the 1,2-phenylene radicals Ph_1 and Ph_2 .

Above all an aliphatic radical R_2 stands for alkyl with 1 to 4 carbon atoms.

An aromatic radical R_1 and R_2 more especially stands for a monocyclic carbocyclic or heterocyclic aryl radical, the latter of which is preferably an azacyclic aryl radical, e.g. a 2-, 3-, or 4-pyridyl radical. These aryl radicals may be unsubstituted or substituted by one or more than one of the same or of different substituents attached to any of the positions available for substitution. Such substituents are exemplified by those listed for the 1,2-phenylene radicals Ph_1 and Ph_2 .

Above all an aromatic radical R_1 and R_2 stands for phenyl, (lower alkyl)-phenyl, (lower alkoxy)-phenyl, (halogeno) - phenyl, (trifluoromethyl) - phenyl, (nitro) - phenyl, (amino)-phenyl, (di-lower alkylamino)-phenyl, (lower alkanoyl)-phenyl or (sulfamyl)-phenyl; pyridyl or (lower alkyl)-pyridyl or thiienyl.

The amino-alkyl group in the compounds of the Formulae I and II, attached to the nitrogen or oxygen atom respectively, more particularly is a primary, secondary or preferably a tertiary amino-lower alkyl group, in which the amino portion is separated from the hetero atom by at least two carbon atoms. The alkyl chain thereof may be straight or branched and preferably contains 2 to 4 carbon atoms. Examples for the amino-alkyl group are the following: 1-amino-ethyl-(2), -propyl-(2), -propyl-(3), -butyl-(2), -butyl-(3), -butyl-(4), -pentyl-(5), -hexyl-(6), -heptyl-(4) or -2-methyl-propyl-(2); 2-amino-propyl-(3), -butyl-(3), -butyl-(4) or -pentyl-(5), 3-amino-butyl-(4) or -pentyl-(5).

The amino-alkyl group preferably contains a secondary or especially a tertiary amino group. It may contain aliphatic, cycloaliphatic, araliphatic or aromatic radicals, such as lower alkyl, alkenyl, alkylene, aza-, oxa-, or thiaalkylene, mono-cyclic cyclo-lower alkyl or alkenyl, mono-cyclic carbocyclic aryl-lower alkyl or monocyclic carbocyclic aryl. These radicals may be unsubstituted or substituted, the aliphatic radicals especially by free, esterified or etherified hydroxy groups, e.g. those mentioned above and the aryl radicals by those substituents mentioned for Ph_1 and Ph_2 .

Examples for such amino groups are the following: mono- or di-lower alkylamino, e.g. methylamino, dimethylamino, N-methyl-N-ethylamino, ethylamino, diethylamino, n-propylamino, di-n-propylamino, isopropylamino, di-isopropylamino, n-butylamino or di-n-butylamino, hy-

hydroxy-lower alkyl-amino, N-(hydroxy-lower alkyl)-N-lower alkyl-amino or di-(hydroxy-lower alkyl)-amino, in which hydroxyl is separated from the amino nitrogen by at least two carbon atoms, e.g. 2-hydroxyethyl-amino, N-(2-hydroxyethyl)-N-methylamino or di-(2-hydroxyethyl)-amino, lower alkyleneimino or hydroxy-alkyleneimino, e.g. ethyleneimino, pyrrolidino, 2-methyl-pyrrolidino, piperidino, 2- or 4-methyl-piperidino, 3-hydroxy- or acetoxy-piperidino, 3-hydroxymethyl-piperidino, 1,6- or 2,5-hexamethyleneimino, 1,7- or 2,6-heptamethyleneimino, lower aza-alkyleneimino, preferably N-lower alkyl-aza-alkyleneimino, e.g. piperazino, 4-methyl-, ethyl-, hydroxyethyl- or acetoxy-ethyl-piperazino, 3-aza-1,6-hexylene imino, 3-methyl-3-aza-1,6-hexyleneimino, 4-aza-1,7-heptyleneimino, 4-methyl-4-aza-1,7-heptyleneimino, lower oxa- or thia-alkyleneimino, e.g. morpholino, 3-methylmorpholino or thiomorpholino, monocyclic cyclo-lower alkyl-amino or N-cyclo-lower alkyl-N-lower alkyl-amino e.g. cyclopentylamino, cyclohexylamino, N-cyclopentyl-N-methylamino, N-cyclohexyl-N-methylamino or N-cyclohexyl-N-ethylamino, monocyclic cyclo-lower alkyl-lower alkyl-amino, e.g. cyclopentylmethylamino or 2-cyclohexyl-ethylamino, phenyl-lower alkyl-amino or N-lower alkyl-N-phenyl-lower alkyl-amino, e.g. benzylamino, N-methyl-N-benzylamino, N-ethyl-N-benzylamino, N-ethyl-N-(1-phenylethyl)-amino or N-methyl-N-(2-phenylethyl)-amino, phenyl- or diphenyl-amino, e.g. p-tolylamino or di-p-anisylamino.

In the amino-alkyl group the alkyl portion, either partially or in toto, may also form part of a saturated heterocyclic ring system, of which the amino group is a ring member and is separated from the hetero atom by at least two carbon atoms. Such amino-alkyl groups are, for example, pyrrolidyl-(3), 1-methyl-pyrrolidyl-(3), piperidyl-(2) or (3)-methyl, piperidyl-(4), 1-ethylpiperidyl-(4) or 1-methyl-piperidyl-(2) or (3)-methyl.

The quaternaries of the present invention are those containing an additional lower alkyl or aralkyl group, e.g. one of those mentioned above, on any tertiary nitrogen atom present.

The salts of the above compounds are pharmacologically acceptable acid addition salts, derived, for example, from the following inorganic or organic acids, such as hydrohalic acids, e.g. hydrochloric or hydrobromic acid, sulfuric acid, phosphoric acid, nitric acid or perchloric acid, aliphatic, alicyclic, araliphatic, aromatic, or heterocyclic carboxylic or sulfonic acids, for example, formic acid, acetic acid, propionic acid, succinic acid, glycolic acid, lactic acid, malic acid, tartaric acid, citric acid, ascorbic acid, maleic acid, hydromaleic acid, pyroacemic acid, phenylacetic acid, benzoic acid, aminobenzoic acid, anthranilic acid, hydroxybenzoic acid, salicylic acid, aminosalicylic acid, embonic acid, nicotinic acid, methanesulfonic acid, ethanesulfonic acid, hydroxyethanesulfonic acid, ethylenesulfonic acid, halogenbenzenesulfonic acid, toluenesulfonic acid, naphthalenesulfonic acid and sulfanilic acid; methionine, tryptophane, lysine and arginine.

Said salts are those of the 4-aminoalkylamino-quinazolines and 1-aminoalkoxy-benzimidazoles itself or of their N-oxides and the quaternaries contain corresponding anions.

The 4-aminoalkylamino-quinazolines, e.g. the compounds of the Formula I, are partly known and described, for example, in French Patent No. 1,404,488, in J. Chem. Soc. 1947, pages 890-899 and in U.S. Patent No. 3,184,462 as well as in copending applications Ser. Nos. 310,152, filed Sept. 19, 1963, now abandoned; 348,861, filed Mar. 2, 1964, now U.S. Patent No. 3,301,855, and 282,242, filed May 22, 1963, now abandoned. Apart from a vaso-dilating and antimalarial activity they show primarily analgesic effects.

We have now found that the 1-aminoalkoxy-benzimidazoles, e.g. the compounds of the Formula II, which primarily show central nervous system depressing effects and

are the subject matter of copending application Ser. No. 484,433 filed Sept. 1, 1965 now U.S. Patent No. 3,300,505, surprisingly potentiate the pharmacological activity, especially the analgesic effects, of the 4-aminoalkylamino-quinazolines, such as those of Formula I. This synergistic effect can be demonstrated in animal tests using, for example, mice as test objects. The compositions of the invention are, therefore, primarily useful as analgesic agents which, depending on the amount of the 1-aminoalkoxybenzimidazole present therein, also provide an additional tranquilizing effect.

Particularly valuable are compositions comprising essentially compounds of the Formulae III and IV.

20 and

in which R₃ stands for hydrogen, lower alkyl or halogen, R₄ for hydrogen, phenyl, (lower alkyl)-phenyl, (halogeno)-phenyl, pyridyl or thienyl, each of R₅ and R₆ for hydrogen, lower alkyl, lower alkoxy, halogen, trifluoromethyl, nitro, amino, di-lower alkylamino, lower alkanoyl or sulfamyl, R₇ for alkyl with 1 to 4 carbon atoms or the radical

or pyridyl or (lower alkyl)-pyridyl, each of m and n for an integer from 2 to 7, Am₁ for di-lower alkylamino, lower alkyleneimino or lower mono-aza-, oxa- or thia-alkyleneimino, and Am₂ for amino, lower alkylamino, di-lower alkylamino, lower alkyleneimino or lower mono-aza-, oxa- or thia-alkyleneimino, Am₁ and Am₂ being separated from the nitrogen or oxygen atom respectively by at least 2 carbon atoms, and pharmaceutically acceptable acid addition salts thereof.

Especially mentioned are compositions which contain as the main active ingredients compounds of the Formulae V and VI

in which R₈ stands for hydrogen or phenyl, each of R₉ and R₁₂ for di-lower alkylamino or lower alkyleneimino, each of R₁₀ and R₁₁ for hydrogen, methoxy, fluoro, chloro, iodo, nitro or sulfamyl and each of m and n for an integer from 2 to 4, and pharmaceutically acceptable acid addition salts thereof, and particular those containing 4-(2-dimethylamino-ethylamino)-quinazoline and 1-(2-diethylamino-ethoxy)-2-phenyl-benzimidazole dihydrochloride. The latter, when given subcutaneously to mice at a dose of 10 mg./kg., increases the analgesic effect of the former in the tail-flick test by about one third, i.e. its ED₅₀ value is only about two thirds in the composition according to the invention in comparison to that of the 4-(2-dimethylamino-ethylamino)quinazoline alone. In case the dose of 1-(2-diethylamino-ethoxy)-2-phenyl-benzimidazole dihydrochloride is increased in the same test to 50 mg./kg., an about five to six fold increase of the angesic potency of 4-(2-dimethylamino-ethylamino)-

quinazoline is observed, i.e. its ED₅₀ is reduced to about 10 mg./kg.; at this dose level also a tranquilizer-like effect is produced with the composition according to the invention.

Accordingly, the present compositions contains the 4-aminoalkylamino-quinazolines and 1-aminoalkoxy-benzimidazoles in a ratio between about 1:10 and 10:1, preferably between about 1:5 and 5:1. A single dosage unit of the compositions according to the invention, which may be administered up to 3 times a day, more particularly contains between about 100 and 600 mg., preferably between about 300 and 500 mg. of the 4-aminoalkylamino-quinazolines, especially those of Formula V, and between about 10 and 150 mg., preferably between about 25 and 100 mg. of the 1-aminoalkoxy-benzimidazoles, especially those of Formula VI.

The compositions of this invention are generally prepared according to methods used in the art of manufacturing pharmaceutical compositions, essentially by combining specified proportions of the pharmacologically active ingredients with a pharmaceutically acceptable organic or inorganic carrier. Usually, the compositions of this invention contain at most equal amounts of the active ingredients and the inert carrier; preferably, they are made up to have from about 1% to at most 50% by weight of the pharmacologically active ingredients in the compositions. In those for oral use (e.g. tablets or capsules), the percentage by weight is from about 5% to at most 80% of the active ingredient. In those for injections (e.g. solutions), the percentage by weight is from about 1% to about 20% of the active ingredients.

In preparing pharmaceutically acceptable dosage unit forms, any one of a wide variety of preparations may be manufactured, such as tablets, capsules, pills, suppositories, solutions or suspensions. In addition to the pharmacologically active component, there may be present additional substances, commonly employed in the art of manufacturing pharmaceutically acceptable dosage unit compositions. These may include excipients, binders, fillers, lubricants, solvents, stabilizers, wetting agents, emulsifiers, buffers, and/or other inert ingredients. Examples of these materials, especially for the orally applicable preparations, are the following: starches, e.g. corn or wheat starch, sugar, e.g. lactose or sucrose, stearic acid, magnesium or calcium stearate, aluminum magnesium silicate (colloidal silica) preparations, talc, tragacanth, alginic acid, acacia or polyethylene glycol. The quantities of these ingredients may vary widely and depend upon the characteristics and the size of the desired, orally applicable form, and/or the method of its manufacture. Encapsulation may be effected using, if necessary, the same excipients as those employed for the preparation of other orally applicable forms, e.g. tablets. Any compatible colors, approved and certified under the provisions of the Federal Food, Drug and Cosmetic Law may be used as a means of identification.

Primary solvents of the solutions for injection according to this invention are water, water-miscible organic solvents, such as lower alkanols, e.g. ethanol, or mixtures of water and water-miscible organic solvents. Other ingredients are added to ensure stable solutions for injection, for example, stabilizers, such as anti-oxidants, e.g. thiourea, sodium sulfide, sodium metabisulfite, ascorbic acid, cysteine hydrochloride, sodium formaldehyde sulfonate, mono-thioglycerol or thiosorbitol, solubilizers, e.g. N,N-diethylacetamide, polyethyleneglycol, ureas or urethanes, buffers and buffer combinations to maintain a preferably pH of about 7, such as, for example, acetic acid, potassium phthalate and sodium hydroxide, potassium dihydrogen phosphate and disodium hydrogen phosphate, potassium dihydrogen phosphate and sodium hydroxide or acetic acid and sodium acetate, salts for making isotonic solutions, e.g. sodium chloride, or any other suitable auxiliary substances, for example other therapeutically active compounds.

The following working examples are illustrative of the invention, but are in no way intended to limit its scope; temperatures are given in degrees centigrade.

Example 1

Preparation of 2000 tablets each containing 0.5 g. of the active ingredients.

Material:

4 - (2 - dimethylamino-ethylamino)-quinazoline	g	800.0
1-(2-diethylamino - ethoxy) - 2 - phenyl-benzimidazole dihydrochloride	g	200.0
Sterotex	g	88.0
Alginic acid	g	42.0
Cellulose acetate phthalate	g	300.0
Anhydrous ethanol	ml	332.0
Acetone	ml	332.0

Procedure.—The quinazoline, benzimidazole and alginic acid are passed through a 20 mesh screen and mixed for 30 minutes. The phthalate is dissolved in the ethanol-acetone mixture and with the solution the powders are wetted and mixed thoroughly. The granulate is dried with warm air, passed through a 16 mesh screen and compressed into tablets using 13/16" diameter dies, modified ball punches.

Example 2

Preparation of 1000 tablets each containing 0.555 g. of the active ingredients.

Material:

4 - (2 - dimethylamino-ethylamino)-quinazoline	G.	500.0
1-(2-diethylamino - ethoxy) - 2 - phenyl-benzimidazole dihydrochloride		55.0
Microcrystalline cellulose		109.0
Polyethylene glycol 6000 powder		18.0
Polyvinyl alcohol powder		18.0
50% aqueous ethanol, q.s.		

Procedure.—The quinazoline, benzimidazole and polyvinyl alcohol are passed through a 20 mesh screen, mixed with the cellulose and the mixture is moistened with the ethanol. The granulate is dried with warm air, passed through a 12 mesh screen, mixed with the polyethylene glycol and compressed into tablets using 14/32" diameter dies, modified ball punches.

Example 3

Preparation of 20,000 tablets each containing 0.2 g. of the active ingredients.

Material:

4-(2 - dimethylamino-ethylamino)-quinazoline	G.	2,000.0
1-(2-diethylamino-ethoxy) - 2 - phenyl-benzimidazole dihydrochloride		2,000.0
Gelatine		300.0
Corn starch (anhydrous)		3,318.0
Talcum		1,250.0
Stearic acid		132.0
Purified water, q.s.		

Procedure.—The quinazoline, benzimidazole and 1,452 g. of the starch are passed through a 16 mesh screen and mixed thoroughly. The gelatin is dissolved in 2,000 ml. water, the solution combined with a suspension of 616 g. starch in 400 ml. cold water and the whole heated on a water bath until a paste is formed. It is combined with the sieved powders using additional water, if necessary. The granulate is passed through a 5 mesh screen, dried at 49° and broken on a 9 mesh screen in the Fitzpatrick mill, knives forward. The granules are mixed with the talcum, stearic acid and the remaining starch and the mixture compressed into tablets using standard concave punches scored and monogrammed.

Example 4

Preparation of 1000 capsules each containing 0.25 g. of the active ingredients.

Material:

	G.
4 - (2 - dimethylamino-ethylamino)-quinazoline	100.0
1-(2-diethylamino - ethoxy) - 2 - phenyl-benzimidazole dihydrochloride	150.0
Lactose	530.0

Procedure.—The ingredients are passed through a 40 mesh screen, mixed thoroughly and 780 mg. thereof filled into each No. 0 gelatin capsule.

The active ingredients used in the examples herein may be prepared as follows:

To a solution of 0.95 g. 4-mercaptop-quinazoline (or its tautomer 3H-quinazolin-4-thione) in 10 ml. 2-dimethylamino-ethylamine is added 10 ml. ethanol. The solution is refluxed for four hours and is then evaporated to dryness under reduced pressure. The solid residue is crystallized from the mixture of acetone and hexane to yield the desired 4-(2-dimethylamino-ethylamino)-quinazoline of the formula

which upon further recrystallizations from cyclohexane melts at 146-148°.

4.0 g. 1-hydroxy-2-phenyl-benzimidazole are dissolved in 50 ml. dimethylformamide at 60° with stirring. The clear solution formed is cooled to 40°, mixed with 1.0 g. of a 53% sodium hydride suspension in mineral oil, stirred at room temperature for 5 minutes and then at an internal temperature of 55-60° for 10 minutes. Thereupon the reaction mixture is mixed with 25 ml. toluene, cooled in an ice bath and then mixed with 12 ml. of a solution of 2-diethylamino-ethyl chloride in toluene containing 0.23 g./ml. The clear amber solution is stirred for 6 hours in an ice bath and allowed to stand overnight at room temperature. Thereupon it is cooled in an ice bath, mixed with 5 ml. 95% ethanol and 100 ml. diethyl ether and filtered. The filtrate is evaporated to dryness in vacuo, the residue taken up in ether, the solution washed with 100 ml. water, the ethereal layer dried over sodium sulfate and evaporated. The remaining light yellow oil is dissolved in diethyl ether, the solution cooled in an ice bath and mixed with ethereal hydrochloric acid. The 1-(2-

diethylamino-ethoxy) - 2 - phenyl-benzimidazole dihydrochloride of the formula

formed is filtered off and recrystallized from methanol-diethyl ether; M.P. 158-160°.

What is claimed is:

1. A pharmaceutical composition comprising a 4-aminoalkylamino-quinazoline of the formula

15 and a 1-aminoalkoxybenzimidazole of the formula

20 in which R8 is hydrogen, each of R10 and R11 is hydrogen or the pharmaceutically acceptable acid addition salt of these compounds, said 4-aminoalkylamino-quinazoline and said 1-aminoalkoxy-benzimidazole being present in the proportion of 1:5 to 5:1.

25 2. A composition as claimed in claim 1, comprising essentially the 4-(2-dimethylamino-ethylamino)-quinazoline and an analgesically potentiating amount of the 1-(2-diethylamino-ethoxy) - 2 - phenyl-benzimidazole dihydrochloride.

30 3. A composition as claimed in claim 1 of which a single dosage unit contains between about 300 to 500 mg. of 4-(2-dimethylamino-ethylamino)-quinazoline and between about 25 and 100 mg. of 1-(2-diethylamino-ethoxy)-2-phenyl-benzimidazole dihydrochloride.
